(57) **CLAIM**

The ornamental design for a slide for an aircraft, as shown and described.

DESCRIPTION

FIG. 1 is a perspective view of a slide for an aircraft. FIG. 2 is a plan view of the slide for an aircraft; and, FIG. 3 is a perspective view of the slide for an aircraft shown in an environment of use.

The broken lines in the drawings depict portions of the slide for an aircraft that form no part of the claimed design. The additional broken lines shown in FIG. 3 depict environment only and form no part thereof.

1 Claim, 3 Drawing Sheets
